TOWEL RACK

George W. Spiegel and Roy H. Morris,
Clintonville, Wis.

Application June 27, 1944, Serial No. 542,376

1 Claim. (Cl. 211—123)

This invention relates to towel racks.

A primary object of this invention is the provision of an improved towel rack incorporating in its construction elements which would otherwise go to waste.

An additional object of this invention is the provision of a towel rack of useful and durable construction at comparatively negligible cost.

A more specific object is the provision of a structure incorporating an otherwise useless fluorescent tube.

A still further object is the provision of a novel method of manufacture and assembly of towel racks.

Other objects will in part be obvious and in part pointed out hereinafter.

Having reference now to the accompanying drawing wherein there is shown a preferred form of this invention concept—

Figure 1 is a perspective view, partially exploded, of the completed assembled towel rack.

Figure 2 is an end elevational view of the device.

Figure 3 is an exploded semi-perspective view of one of the brackets employed in supporting the central fluorescent tube and its associated parts, and

Figure 4 is a section taken along the line 4—4 of Figure 2 as viewed from the front.

Like reference numerals refer to like parts throughout the several views of the drawing.

Having particular reference now to Figure 1, there is shown at 10 a fluorescent tube which may, of course, be good but which is preferably a burned out or otherwise useless tube, positioned and adapted for use as a towel rack. Tube 10 is adapted to be supported by a pair of reversible brackets 11, provided with relatively right angularly disposed flanges 12, said flanges having apertures 13 therethrough through which may be passed suitable screws 14 for securing the same to a wall or other desired locality.

As is known, conventional fluorescent tubes are of a fixed diameter and provided with end caps 15, from each of which caps extend a pair of prongs 16 which, when the tube is in use, serve as contacts for the electrical circuit therethrough. Each of brackets 11 has adjacent its outer end a pair of spaced holes 17 so positioned and spaced as to receive prongs 16 on the end caps 15 of tube 10. Positioned at an intermediate point between holes 17 is a third hole 20 through which is adapted to be passed a screw 21 (see Figure 3) threadedly to engage a recess 22 (see Figure 4) tapped into the end cap 15 of tube 10. If desired

5 a protector cup 23 may be provided to cover prongs 16. Cup 23 is, as best shown in Figure 4, provided with a countersunk, centrally disposed depression 24 into which the head of screw 21 is adapted to fit to present a flush exterior surface.

From the foregoing the method of installation and assembly of the device should be readily understood. One of the brackets 11 is first secured to a wall or other suitable surface by means 10 of screws 14 passed through holes 13 and one pair of prongs 16 inserted in holes 17. End cap 23 is then placed in position and screw 21 passed through the central aperture thereof and through hole 20 into threaded engagement with tapped hole 22 in end cap 15 of tube 10. The other of brackets 11 is then secured to the opposite end of tube 10 in a similar manner, and subsequently, in order to insure proper spacing of the brackets, secured to the wall in such manner that tube 10 15 is substantially parallel to the floor.

From the foregoing it will be seen that there is herein provided a device which permits the utilization of an otherwise useless fluorescent tube in a manner to make a new and useful article of manufacture, which may be readily and simply assembled and placed in position and which may be manufactured at a negligible cost. Thus the instant invention achieves all the objects above set out and others including many advantages of great practical utility and commercial importance.

As many embodiments may be made of this inventive concept and as many modifications may be made in the embodiment herein shown and described, it is to be understood that all matter hereinbefore set forth is to be interpreted merely as illustrative and not in a limiting sense.

We claim:

40 In a towel rack, a towel supporting bar comprised of a fluorescent tube, a pair of spaced prongs at opposite ends of said tube, each end of said tube having a threaded recess therein, a pair of brackets, each having a pair of spaced holes adapted to receive said prongs, and each having a third hole disposed between said pair of spaced holes, end caps adapted to be positioned on the exterior side of said brackets to cover said prongs and having centrally disposed holes therethrough, screws adapted to be passed through each of said centrally disposed holes and each of said third holes, threadedly to engage said recesses, and means for mounting said brackets.
